CLAIM

I claim the ornamental design for a mouth tape, as shown and described.

DESCRIPTION

FIG. 1 is a front view of the mouth tape;

FIG. 2 is a rear view of the mouth tape;

FIG. 3 is a top view of the mouth tape, the bottom view being a mirror image;

FIG. 4 is a right side view of the mouth tape, the left side view being a mirror image; and,

FIG. 5 is a perspective view of the mouth tape.
